Assistant Examiner — Sydney M Evans

(57) **CLAIM**

The ornamental design for an intelligent electronic door lock, as shown and described.

DESCRIPTION

FIG. 1 is a front perspective view of an intelligent electronic door lock showing my new design.

FIG. 2 is a rear perspective view of an intelligent electronic door lock.

FIG. 3 is a front view of an intelligent electronic door lock.

FIG. 4 is a rear view of an intelligent electronic door lock.

FIG. 5 is a left side view of an intelligent electronic door lock.

FIG. 6 is a right side view of an intelligent electronic door lock.

FIG. 7 is a top view of an intelligent electronic door lock.

FIG. 8 is a bottom view of an intelligent electronic door lock; and,

FIG. 9 is a perspective view of an intelligent electronic door lock in a position of use.

The broken lines illustrate portions of the intelligent electronic door lock and environmental structure that form no part of the claimed design.

1 Claim, 9 Drawing Sheets
